(57) **CLAIM**

The ornamental design for a bonding and grounding clamp, as shown and described.

DESCRIPTION

FIG. 1 is a perspective view of the bonding and grounding clamp of my design;

FIG. 2 is a side elevational view thereof, the opposite side being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken line portion of the figure drawings is included to show unclaimed subject matter only and forms no part of the claimed design.
